UNITED STATES PATENT OFFICE.

JAMES R. COOK AND WALTER P. MIESEN, OF NARBERTH, PENNSYLVANIA.

DESIGN FOR A BADGE OR SIMILAR ARTICLE.

Application filed June 15, 1923. Serial No. 6,501. Term of patent 7 years.

To all whom it may concern:

Be it known that we, JAMES R. COOK and WALTER P. MIESEN, citizens of the United States, and residents of Narberth, county of Montgomery, State of Pennsylvania, have invented a certain new, original, and ornamental Design for a Badge or Similar Article, of which the following is a specification, reference being had to the accompanying drawing, forming part thereof.

The figure is a face view of our new design for a badge, or similar article.

We claim:—

The ornamental design for a badge, or similar article, substantially as shown.

JAMES R. COOK.
WALTER P. MIESEN,
